PERIMETER

William Feinblom, New York, N. Y.

Application December 24, 1942, Serial No. 470,107

6 Claims. (Cl. 88—20)

This invention relates to perimeters, devices for testing and determining the angle of vision and the location of blind spots in the human eye.

It is an object of this invention to provide a portable perimeter that is both simple in operation and accurate in its results.

Another object of this invention is to provide a perimeter in which the person undergoing the test personally actuates the recording mechanism.

One of the features of my device is its simplicity of construction.

Another feature resides in the positive recording mechanism which allows the person being tested no chance for after thoughts, reconsiderations or rationalizations.

Still another feature of the invention resides in that a dark room is not necessary for its efficient operation.

Other and further objects and features will become apparent from the following specification and the accompanying drawings in which like numerals of reference indicate identical parts, and in which:

Fig. 1 is a cross-section through the perimeter as a whole; Fig. 2 is an end view of the perimeter, taken along line 2—2 of Fig. 1, showing the control knob and the recording chart; Fig. 3 is a section of the control knob taken along line 3—3 of Figs. 1 and 2; and Fig. 4 is a schematic diagram of the electric circuit employed in the perimeter.

In the drawings, 1 is a horizontal hollow tube terminating at one end in the substantially semi-spherical bowl 2 and in the wide flange 3 at the other end. The tube 1 is welded centrally to tube 4 and the latter screws into base 5 on which the complete mechanism is supported.

Rotatively supported within tube 1, as it extends into bowl 2 and out through flange 3, is tube 6. The end of tube 6 within bowl 2 is open. Across this open end, pivoted on pin 7, is positioned mirror 8. Pin 7 is supported in the walls of tube 6. Intermediate one side of the mirror and said wall, and keyed to pin 7, is worm wheel 9. Wheel 9 is controlled by the worm 10. The worm, fastened at the end of rod 11, is controlled by the small knob 12 positioned at the other end of the rod. Rod 11 is rotatably supported within tube 6 and is rotatable independently of the rotation of said tube.

The end of tube 6 which passes through flange 3 is capped by the large knob 13. By means of knob 13 tube 6 is rotated. Fastened to rod 11, and positioned within a recess in the back of

knob 13, lies spur gear 14. This gear meshes with the rack 15 slidably supported in the T-slot 16 in knob 13 (Fig. 3). Riveted to an extreme end of the rack is the flat spring-metal strip 17 which terminates at its free end in the stylus 18. Attached to a substantial portion of the mid-section of spring 17 is the iron armature 19. Rotation of knob 13 rotates tube 6, mirror 8, and stylus 18 with respect to tube 1. Rotation of knob 10, 12 extends or retracts the stylus and simultaneously tilts the mirror 8 with respect to the axis of tube 1.

Within tube 6, casting its light through aperture 20 and lens 21 onto mirror 8, is light bulb 40. The lens and aperture are so chosen that a comparatively sharp spot of light is focused from the bulb onto the inner surface of bowl 2. Also within tube 6, arranged in operable relation to the armature 19, is positioned the electric magnet 22. One lead of the electric current to both the bulb and the magnet is grounded; the other leads, 23 and 24, are connected respectively to the insulated slip-rings 25 and 26 on the outside of tube 6. By means of the wipers 21, leads 23 and 24 are continued by leads 23' and 24' to the relay 28. The relay is actuated by the push-button 29 positioned without the instrument but connected thereto by the flexible electric cord 30.

The electric circuit employed is shown in Fig. 30. Current is derived from a standard source through plug 31, wires 32, and transformer 33. The relay 28 is a standard commercial one, available on the market today, wherein the armature closes one circuit and opens another on being 35 attracted by the electro-magnet. The relay is equipped with a manual reset so that once the first circuit is opened, knob 34 of cam 34' must be manipulated to close that circuit again. Knob 34 is shown in Figure 1, cam 34' is shown in the 40 diagram, Figure 4.

With the relay in the normal or reset position the current is on in the light circuit. When button 29 is depressed, the relay opens the light circuit and closes the electro-magnet circuit; 45 whereupon said electro-magnet 22 draws armature 19, together with stylus 18, toward itself. With this movement the stylus will make a mark on the graph paper 35 held by clips 36 to the face of flange 3. Bulb 40 can not light again until 50 relay 28 has been reset.

Across the open face of bowl 2 is stretched an opaque, elastic sheet 37. In line with the axis of tube 6, sheet 37 is provided with a hole 38 to accommodate the human eye as would an eye cup. Hole 38 is framed with wire and is supported by a

wire spider 39 from the edge of bowl 2. The spokes of the spider are so arranged that when a person places his eye at hole 38 the spokes will not interfere with the protruding features of the face such as the nose, chin and brow. The elastic sheet 37, on the other hand will yield to permit such protrusion; the eye, however, will be kept at hole 38 in fixed predetermined relation to the bowl.

The use of the above perimeter is simple. Chart 35 is so calibrated and so inter-related to the extensions of the stylus 18 and the tilting of mirror 8 that the angle A, the angle included between the axis of the instrument and the line from the center of aperture 38 to the spot of light reflected from the mirror onto the inner surface of the bowl, will be indicated by the stylus on said chart for any setting of the instrument. The patient has one eye blind-folded and places his other eye against aperture 38. Knob 13 is rotated until stylus 18 indicates the meridian for which the eye is to be tested. Then knob 12 is rotated so that the mirror is tilted to reflect light on the back of sheet 37. Then the bulb 40 is lit. The mirror is then tilted slowly to bring the spot of reflected light gradually from the rim of the bowl 2 towards its center. When the patient first becomes aware of the light spot he is supposed to press the button 29. As he does so, the light immediately goes out and the stylus records the angle of perception. The operations may be repeated for as many meridians as desired.

The patient can not waver too long to express his judgment, nor can be retract his impulse once he has pressed the button to make the permanent record. In order to avoid distraction and to help him focus his eyes forward, a small section 41 of the back of the mirror has its silvering removed to allow a pin-point of light from bulb 40 to shine directly into the patient's eye. If it is desired to test for color sensitivity, diaphragm 20 may be replaced by a color filter. In order to make the instrument more portable, transformer 33 may be replaced by dry batteries. The transformer is used because it is felt not desirable to use high voltage current in a device of this sort.

From the foregoing description it will be seen that I have devised a simple, inexpensive and efficient machine to accomplish the objects set forth. While I have described the simplest elements adapted to accomplish these purposes, it is obvious that various changes in form and proportion may be resorted to, such as changing the shape of the bowl, or the electrical components, the source of light, or the patient-recorder link may be resorted to without departing from the spirit or sacrificing any of the principles of the invention.

What I claim is:

1. A perimeter comprising a substantially semi-spherical bowl, a diaphragm across the face of the bowl having an aperture adapted to accommodate the eye to be tested, a mirror positioned within the bowl, a light source directed to the mirror, and means to vary the angular position of the mirror in any meridian with respect to the bowl so that light can be reflected by the mirror on to any portion of the interior surface of the bowl.
- 10 2. A perimeter comprising a substantially semi-spherical bowl, a diaphragm across the face of the bowl having an aperture adapted to accommodate the eye to be tested, a mirror positioned within the bowl, a light source positioned behind the bowl, means directing the light rays from the light source to the mirror through an aperture in the bowl, and means to vary the angular position of the mirror in any meridian with respect to the bowl so that light can be reflected by the mirror to any portion of the interior surface of the bowl.
- 15 3. A device substantially as described in claim 1 wherein the means which varies the angular position of the mirror is linked and synchronized with indicating means without the bowl to indicate the angular position of the mirror with respect to the bowl.
- 20 4. A perimeter comprising a substantially semi-spherical bowl, means to position the eye at a predetermined position at the face of the bowl, a rotatable tube in axial alignment with the bowl, one end of the tube positioned within the bowl at the rear thereof through an aperture therein, a mirror pivotally mounted at said end of the tube, a light source mounted within the tube, means to direct light from the source to the mirror, and means to tilt the mirror on its pivotal mounting so that the light rays may be reflected on to the interior surface of the bowl at any angle with respect to the axis of the tube.
- 25 5. A device substantially described in claim 4 wherein the means that tilts the mirror is linked and synchronized with indicating means without the bowl to indicate the angular position of the mirror.
- 30 6. A perimeter comprising a substantially semi-spherical bowl, a diaphragm across the face of the bowl having an aperture adapted to accommodate the eye to be tested, a rotatable tube in axial alignment with the bowl, one end of the tube positioned within the bowl at the rear thereof through an aperture therein, a light source mounted within the tube, means to project a light spot from said source onto the inner surface of the bowl, and means to vary the position of the light spot on said inner surface.
